US00D642861S

(12) **United States Design Patent**
Samartgis

(10) **Patent No.:** **US D642,861 S**
(45) **Date of Patent:** **** Aug. 9, 2011**

(54) **LID AND SEAL FOR A CONTAINER**

(75) Inventor: **Jim Samartgis**, Melbourne (AU)

(73) Assignee: **The Decor Corporation Pty Ltd.**,
Scoresby, Victoria (AU)

(**) Term: **14 Years**

(21) Appl. No.: **29/353,537**

(22) Filed: **Jan. 11, 2010**

(30) **Foreign Application Priority Data**

Aug. 14, 2009 (AU) 13095/2009

(51) **LOC (9) Cl.** **07-02**

(52) **U.S. Cl.** **D7/392.1**

(58) **Field of Classification Search** D9/454,
D9/453, 452, 445, 444, 435, 425; D7/629,
D7/392.1, 391; D3/318; 220/802, 784, 781,
220/780; 215/317, 316, 270

(57) **CLAIM**

The ornamental design for a lid and seal for a container, as shown and described.

DESCRIPTION

FIG. 1 is a front perspective view, from above, of the claimed design;

FIG. 2 is a rear perspective view, from beneath, of the claimed design;

FIG. 3 is an exploded front perspective view, from above, of the claimed design, showing the lid component and seal component separated;

FIG. 4 is an exploded rear perspective view, from beneath, of the claimed design, showing the lid component and seal component separated;

FIG. 5 is a top plan view of the lid component of the claimed design;

FIG. 6 is an underneath plan view of the lid component of the claimed design;

FIG. 7 is a top plan view of the seal component of the claimed design;

FIG. 8 is an underneath plan view of the seal component of the claimed design;

FIG. 9 is a left or right side view of the lid component of the claimed design. The left side view is the same as the right side view;

FIG. 10 is an end view of the lid component of the claimed design. Both end views are the same;

FIG. 11 is a left or right side view of the seal component of the claimed design. The left side view is the same as the right side view; and,

FIG. 12 is an end view of the seal component of the claimed design. Both end views are the same.

The broken line showing of a vent is included for the purpose of illustrating environmental structure and forms no part of the claimed design.

1 Claim, 9 Drawing Sheets
